(57) **CLAIM**

The ornamental design for a free-standing batting practice apparatus, as shown and described.

DESCRIPTION

FIG. 1 is a front perspective view of a free-standing batting practice apparatus showing the new design;
FIG. 2 is a front elevation view thereof;
FIG. 3 is a back elevation view thereof;
FIG. 4 is a left side elevation view thereof;
FIG. 5 is a right side elevation view thereof;
FIG. 6 is a top plan view thereof; and,
FIG. 7 is bottom plan view thereof.

1 Claim, 7 Drawing Sheets
